UNITED STATES PATENT OFFICE.

WILLIAM DEANE HAM, OF WASHINGTON, DISTRICT OF COLUMBIA, ASSIGNOR TO THE HAM'S METHOD ENGINEERING COMPANY, OF WASHINGTON, DISTRICT OF COLUMBIA, A CORPORATION OF MARYLAND.

ORNAMENTING CONCRETE WALLS.

Application filed January 5, 1926. Serial No. 78,444.

This invention relates to the construction of concrete walls for buildings and particularly to the application of decorative features to the walls.

5 The most serious drawback to the use of concrete as a building material, especially for residence construction or any other work requiring an attractive surface, has been the lack or apparent lack of decorative possibilities.

10 To use tile or other imbedded ornamentation it becomes necessary to fasten such decorative material securely to the inside of the mold surface and this is usually done by

15 means of large headed tacks or wire staples passing through holes made in the outer mold or form, requiring a great deal of time in making measurements and care and accuracy in placing them to make the work attractive.

20 To tamp around or close to such ornamentation has usually resulted in damage or displacement, which must later require a patch to be made on the outer surface of

25 the wall. As added material such as is necessary to use in covering these defects can not be made to look like the original molded wall, the resulting patch is always a very noticeable and unsightly disfigurement.

30 Since the tamping cannot be done successfully around decorative material, the concrete mass in the wall must be vibrated or settled into place around this ornamentation by means of mallet blows applied to the outside of the mold or form.

35 Mallet blows sufficient to cause the necessary or proper vibration applied to ordinary wooden forms would split them and if the forms were made of a thickness sufficient to resist the mallet blows they would not permit sufficient

40 vibration to produce good results. The vibration also when applied to steel sheets reinforced with angle or U-bars would cause the rivets to pull through the sheets and quickly destroy the effectiveness of the form.

45 One of the main objects of my invention is to provide a method of securing the ornamentation or the decoration to the mold forms quickly and in a manner which avoids any disfigurement of the finished wall and which requires no subsequent patching.

In constructing concrete walls in accord-

ance with my invention, heavy steel plates may be used, and in such manner that they require no rivets, threaded bolts or nuts to hold them in place. These plates are provided with perforations or holes preferably arranged in regular rows so that almost any desired decoration may be fastened to the inner surface of the plates by means of strands 60 of fine wire or wire staples passed around the decorative object and through the perforations, the ends of the wire or staples being twisted together upon the outside of the plates.

65 After the perforations have been drilled in the plates, the holes or perforations may be closed by filling them with any cementitious material that will hold the concrete and will resist the vibration during the malleting operation and yet may be readily removed with a hand punch wherever it is necessary to pass the wires or staples through the plate in securing the decorative objects in position in the mold.

70 The decorative possibilities which are thus provided are almost unlimited since almost any size, shape or weight of decorative tile or other object may be fastened to the inner face of the mold plates by means of soft 80 annealed wire of the proper gauge.

75 My mold plates prepared as described with a multiplicity of puncturable sealed perforations are also especially adapted for panel work because of the ease with which inserts 85 formed of any suitable material, such as wood or rubber, may be attached to the surface of the inner side of the mold plate by means of wires or staples passed through or around the panel work, the ends being 90 threaded through the perforations and twisted together outside of the plate.

In practice I have used steel plates of ten or twelve gauge material, approximately three-sixteenths of an inch thick. These 95 plates may be inserted in the wall mold in any desired position. If the mold boards are one and three-sixteenths inches thick and the plates are made flush with the outer surface of the boards, then the resulting panel 100 will be raised or will stand out one inch from the surface of the wall. If the outer surface of the plate is made flush with the inner surface of the mold boards, the resulting pan-

el will be imbedded or sunken three sixteenths of an inch back of the front face or surface of the wall.

When an ornamentation or decorative object is fastened against the inner surface of a mold plate in the manner described, it is necessary to prevent the cement poured into the mold from entering between the plate and the front face of the ornamentation. 5 For this purpose a piece of paper having the configuration of the object may be pasted to the plate and the object may then be pasted to the paper before being secured with the wires. After the mold has been removed 10 from the wall, the paper may be soaked and washed off, leaving the ornamentation clean and free from cement. I may also prevent the cement in the mold from flowing in between the ornamentation and the mold plate 15 by applying melted paraffine or other suitable material around the marginal edge of the ornamental object thus forming a seal between the plate and the margin of the object.

20 25 In order to more completely describe my invention, I shall refer to the accompanying drawings, in which:

Figure 1 is a perspective view of a mold for constructing concrete walls and embodying the features of my invention;

30 Figure 2 is a partial sectional view on the line 2—2 of Fig. 1;

35 Figure 3 is a fragmentary vertical sectional view of the concrete wall formed in the mold shown in Figure 2, and showing the manner of inserting a precast ornament;

40 Figure 4 is a fragmentary vertical sectional view similar to Figure 2 showing the manner of inserting ornamental tiles in the mold in accordance with my method claimed herein;

45 Figure 5 is a front elevation of the tile ornament inserted in the concrete wall in the manner illustrated in Figure 4;

50 Figure 6 illustrates an ornamental panel having the figures standing out in relief;

55 Figure 7 is a vertical sectional view of a mold taken on the line A—A of Figure 6, showing the manner of casting the panel of Figure 6 in the concrete wall;

Figure 8 illustrates an ornamental panel recessed in the face of a concrete wall and having the ornamental figure in relief;

60 Figure 9 is a vertical sectional view illustrating the manner of casting the ornamental panel of Figure 8 in the concrete wall;

Figure 10 illustrates in front elevation, a portion of a concrete wall having V-joints embedded into the face of the wall to produce the effect of the well-known ashler courses;

65 Figure 11 is a fragmentary vertical sectional view of a mold arranged to form the wall shown in Figure 10;

66 Figure 12 illustrates a front elevation of

an ornamental panel recessed in a concrete wall and having the main ornamental figure in intaglio;

Figure 13 is a fragmentary vertical sectional view of a mold structure for casting 70 the ornamental panel of Figure 12 in a concrete wall, the section being taken on the line B—B of Figure 12;

Figure 14 is a front elevation of a wall section showing a pre-cast ornamental panel 75 inserted in a recess molded in the concrete; and

Figure 15 is a vertical sectional view on the line A—A of Figure 14, to show that the ornament may be partly in relief and partly 80 in intaglio.

I have illustrated in Figure 1 a mold form for pouring a concrete wall constructed in accordance with my invention as set forth in my prior application, Serial No. 739,189. 85 In this structure the mold boards 10 are firmly secured in position against the vertical channel bar brace members 12 by the removable spacers 14, carried by spacer bars 15 by which they are removed after the concrete has been poured. My present invention pertains to the method of applying ornamentation to concrete walls. For this purpose, I provide metal plates which may be embodied in the mold walls and to which 95 the ornamentation, decorative objects or dies may be attached.

These metal plates or panels 16 may be of any desired size and may consist of a single plate or a plurality of plates, at 16, 16^a, etc. 100 Each plate is provided with a multiplicity of perforations, usually extending throughout the area of the plate, by drilling small holes 18 in symmetrical arrangement, preferably in rows extending perpendicular to each 105 other. When two or more plates are placed side by side to form a panel, as shown in Figure 1, the perforations at the edges may be semi-circular so that the matched holes at the joint will permit the wire ties 17, which 110 bind the opposite wall mold boards together, in the manner described in my prior application, to pass through these matched holes.

The metal panel plates 16, extend from the middle of one brace bar 12 to the middle 115 of the next brace bar and when placed in position, they are firmly secured by the removable spacers 14.

In Figure 2, I have shown the manner of providing a recess in a concrete wall in 120 which a pre-cast ornament may be inserted. The metal panel plate 16 is positioned with its rear face flush with the inner sides of the wooden mold boards 10. As the mold boards are usually one and three-sixteenths 125 inches thick while the metal plate is only three-sixteenths of an inch in thickness, filler strips 19, one inch thick are inserted at the margins of the plate between the brace bars 12 and the plate. A block 20, the size 130

- and shape of the desired recess is then secured to the rear face of the plate by means of wires 21 passing over the block with the free ends extending through the perforations 18 from which the cement filler has been punched. After the ends have been twisted together, the wires may be made taut by driving wedge blocks 23 thereunder in the manner shown in Figures 1 and 2.
- 10 When the concrete wall 25 has been completed, the pre-cast ornament 24 may be inserted and cemented in place in the recess thus prepared, as illustrated in Figure 3.
- When the ornamentation or decorative object is to be cast directly in the wall as the concrete is poured in the mold, the method employed is illustrated in Figure 4. The metal panel plate is secured in the mold wall in the manner previously described. If, for instance, the ornamental tiles 30 surrounded by the border tiles 31 are to constitute the decorative panel as illustrated in Figure 5, these tiles are fastened to the rear face of the plate 10 in the same manner as the die block in Figure 2. After the concrete has been poured, the plate is vibrated by striking it with hammer blows, thereby causing the cement to flow into all of the crevices or angles 30 around the marginal edges of the tiles. After the cement has set, the wires 21 are cut and the mold plate is removed together with the mold boards. The paper which was pasted between the face of the tiles and the plate 35 to exclude the cement is then moistened and washed off, leaving the tiles clean and unmarred. The short projecting ends of the fine wires 21 which held the tiles in position, are clipped close to the face of the tiles, the portions extending behind remaining embedded. No patching or pointing up is required and hence there results a perfect unblemished wall with the ornamentation embodied therein.
- 45 One of the most important advantages to be obtained from the use of my invention resides in the facility with which the ornamentation may be molded in the concrete of the wall, either in relief or in intaglio. If it is desired to form a raised panel with the decorative object standing out in relief therefrom, such for instance, as that shown at 32 in Figure 6, the die for said ornamentation may be secured in the mold wall in the manner shown in Figure 7. Since the ornamentation is to stand out in relief from the wall, the metal panel mold plate 16, is made to fit between the vertical channel iron brace members 12 and is fastened there- 50 to at the proper distance forward of the mold boards 10 in any suitable manner, as by interposed marginal strips 19 between the mold boards and the plate, and marginal strips 19 between the front face of the plate 60 and the liner bars or pipes 27, which con-

nect the vertical brace bars 12, as illustrated in Figure 1. The forming die or matrix 35 for the ornament 32, may be constructed of any suitable material, such as gelatine, rubber, plaster, etc. The die is tied to the rear 70 face of the perforated panel plate by means of the wires 21 in the manner previously described. The margins of the raised ornament may be framed in a raised bevelled edge 36.

After the concrete has been poured into the mold, the plate is vibrated by proper blows of a mallet to cause the soft cement to penetrate into every detail of the die. When the concrete has set, the tie wires 21 are cut to free the die from the plate 16 and the mold walls are removed. The die 35 is then carefully removed, leaving the ornamentation in finished condition as an integral part of the wall, the ornamentation 85 32 standing out in relief and framed by the raised margin 36. When the ends of the fine wires 21 are slipped close to the wall they are invisible. As no nails, bolts or screws were used in securing the die to the 90 mold walls there are no traces of the fastening means to be pointed up.

My method is equally applicable to the formation of ornamental panels which are recessed in the face of the wall and in which the ornamental figure or object is either in relief or in intaglio. To make this application of my invention clear, I have illustrated in Figure 8, an ornament 32, forming a raised figure within a recessed panel 32 in the wall and in Figure 9, I have shown the manner of molding it in the construction of the wall. Since the entire panel is to form a recess in the face of the wall, the metal panel mold plate 16 is set back of the front face of the mold boards 10 the desired distance by interposing marginal strips or blocks 19 of the proper thickness between the front face of the plate and the frame brace members 12. The plates 16 are wedged in position by the removable spacers 14 as previously explained. The mold die 35, constituting the matrix for the ornament 32, is fastened to the rear face of the perforated metal plate by fine tie wires 21, as before. 110 The remaining steps of the method are the same as for the figures previously described.

In case it is desired to produce the effect of ashler courses in the face of the wall, such as illustrated in Figure 10, as for instance in the lower courses of a building, at the corners, etc., this may be done very readily by my method of quickly attaching die members to the mold plates in a manner to be readily detached or separated therefrom. 115 For this purpose, I attach to the perforated metal plates 16, strips 40, triangular in section, and positioned to properly form the V-joints 41 of the ashler courses as indicated in Figure 11. This can be done very ac- 120 125 130 135

curately because of the symmetrical arrangement of the perforations which extend throughout the plates in rows perpendicular to each other. The vertical strips 40 are properly cut at the ends to miter into corresponding notches in the horizontal strips as will be evident. Inasmuch as these bevelled strips are free from the plates when the fastening wires 21 are severed, the strips will remain in position within the V-joint recesses when the plates are removed from the wall and may then be carefully withdrawn without marring the sharp edges of the V-joints. This results in the wall face marked off into rectangular blocks 45. I have also devised a method of producing a rock-face or other roughened surface effect upon the rectangular faces 45. When the bevelled or triangular strips 40 have been wired in position, I pour upon the rear face of the plate 16, in the rectangular spaces bounded by the strips, a plastic composition which may be made by mixing melted rosin with bees-wax. This is preferably done with the plate 21 in inverted horizontal position before securing it in position in the mold wall. As soon as the mixture has hardened sufficiently to retain an impression, but while still plastic, I pass over it a suitable tool which produces indentations in a reversed pattern to thereby form a die in accordance with the pattern desired upon the surface of the blocks in the finished wall. The tool which is used to form the indented pattern in the wax composition may be constructed in various ways and may be applied in a manner suitable to the particular tool. For instance, it may be in the form of a roller having the desired pattern upon its surface and which is rolled across the surface of wax while it is still plastic. Or the tool may be in the form of a cutting tool or one adapted to scratch the wax surface. I deem it advisable to disclose another application of my method of applying ornamentation. It is sometimes desirable to produce a sunken or recessed panel in the wall within which the main ornamental figure is also sunken or in intaglio, such for instance, as illustrated in Figure 12. I have shown the marginal frame surrounding this sunken panel formed of two parallel beads 46^a and 47^a, in stepped relation, the inner one being ornamented with a decorative pattern in relief. The main intaglio figure, 48, is sunken entirely below the plane of the surface 49 of the recessed panel. To produce these results, the perforated metal plate 16 is positioned with its inner face flush with the inner sides of the wooden mold boards 10. Rectangular panel boards 46 and 47 in superposed relation are positioned to form the die for the panel recess and against the center of the rear face of the panel board 47 is positioned the die 48^a

having the configuration of the main ornamental figure 48. The panel boards 46 and 47 and the die member 48^a are then fastened to the perforated metal mold plate by means of the tie wires 21 which pass through suitable holes drilled through the panel boards and through corresponding perforations 18 in the plate. My method of removably attaching the die members to the perforated metal mold plate so that they may be absolutely detached from each other before the mold walls are removed ensures the integrity of the molded ornamentation and removes all danger of marring its form and beauty during the removal of the mold parts. Thus in the construction shown in Figure 13, after the fastening wires 21 have been cut, the metal plate 16 may be removed without disturbing the panel boards 46 and 47. These may then be removed carefully one at a time, in order not to injure the marginal beads 46^a and 47^a. Finally the die member 48^a may be withdrawn without any danger of injury to the indented ornamentation. The projecting wires 21 are clipped close to the surface of the panel 49, the wires being so fine that the ends are practically invisible.

In Figures 14 and 15, I have shown pre-cast ornamentation provided with raised and intaglio parts and set into a recess prepared in the manner illustrated in Figure 2, so that the raised and depressed portions will extend respectively beyond and behind the face plane of the wall.

The advantage of my method of applying the ornamentation resides not only in the facility with which the decorative object may be quickly and accurately fastened in proper position within the mold, but also in the facility with which the mold parts may be removed, leaving the wall in perfect condition with the ornamentation embedded therein without the necessity for patching or pointing up around the ornamentation.

I claim:

1. The method of applying surface ornamentation to concrete walls, which comprises fastening the decorative objects to the inner face of a metal mold plate before the concrete is poured into the mold by passing wires about the objects and through perforations in the plate.

2. The method of applying surface ornamentation to concrete walls, which comprises fastening the decorative objects to the inner face of a metal mold plate before the concrete is poured into the mold by passing wires about the objects and through perforations in the plate and securing the free ends of the wires.

3. The method of applying surface ornamentation to concrete walls, which comprises inserting in the mold wall a metal plate having puncturable sealed perfora-

tions, positioning a decorative object against the inner surface of the plate, passing wires across the rear of the object, threading the free ends of the wires through the plate 5 perforations and securing the ends of the wires.

4. The step in the method of applying surface ornamentation to concrete walls, which comprises inserting in the mold wall 10 a metal plate having puncturable sealed perforations, whereby die members may be secured within the mold by inserting fastening media through said perforations.

5. A wall member for molds for casting 15 concrete building walls comprising a metal

plate provided with a plurality of perforations which are sealed or closed with a puncturable material.

6. A wall member for molds for casting concrete building walls comprising a metal 20 plate provided with a plurality of symmetrically disposed perforations arranged in rows and which are sealed or closed with a puncturable material.

7. In a wall member as set forth in claim 25 5, said sealing material having a cementitious composition.

In testimony whereof I affix my signature.

WILLIAM DEANE HAM.
